DESIGN FOR A BOTTLE

Frasier Smith, Wheeling, W. Va., assignor to
Hazel-Atlas Glass Company, Wheeling, W. Va.,
a corporation of West Virginia

Application July 6, 1934, Serial No. 52,473

Term of patent 14 years

To whom it may concern:

Be it known that I, FRASIER SMITH, a citizen of the United States, residing at Wheeling, in the county of Ohio and State of West Virginia, have invented a new, original, and ornamental Design for a Bottle, of which the following is a specification, reference being had to the accompanying drawing forming part thereof.

Figure 1 is a perspective view of a bottle showing my new design,

Figure 2 is a side elevational view thereof; and
Figure 3 is a horizontal sectional view thereof
taken on the line 3—3 of Fig. 2.

I claim:

The ornamental design for a bottle, as shown.
FRASIER SMITH.
